FRANK HENRY SLEEPER, OF WORCESTER, MASSACHUSETTS, ASSIGNOR TO SLEEPER & HARTLEY, INC., OF WORCESTER, MASSACHUSETTS, A CORPORATION OF MASSACHUSETTS.

SPRING-COILING MACHINE.

1,266,070.

Specification of Letters Patent. Patented May 14, 1918.

Application filed May 6, 1914. Serial No. 836,628.

To all whom it may concern:

Be it known that I, FRANK HENRY SLEEPER, of Worcester, county of Worcester, State of Massachusetts, have invented a new 5 and useful Improvement in Spring-Coiling Machines, of which the following is a specification.

My invention relates to that class of machines used for coiling or forming wire 10 springs, and more particularly to that type of spring coiling machine having feed rolls, which take the wire from the coil and feed a predetermined length; devices for coiling the spring into any desired spring form,— 15 either open or close coil, barrel, coned, two-diameter, &c; and devices to sever the fed wire at the coiling point, while the feeding devices are stopped, allowing the completed spring to drop before the coiling of the 20 next spring has begun.

My improvements are concerned with a number of features adapted to machines of this kind, and the aim of my invention has been to provide a machine in which all of 25 these improvements are incorporated in such manner as to allow of very speedy adjustment, and very ready accessibility.

One of my improvements relates to the feeding mechanism,—having in view the 30 combining of intermittently-operating devices capable of feeding successive lengths of wire within very close limits of accuracy, with means to adjust and regulate said length of feed easily and conveniently.

Another of my improvements is concerned 35 with the providing of a holder for the coiling tools so constructed and arranged with regard to the tools contained therein, and to the machine frame in which it is supported, 40 that it may readily be reversed to coil either right-hand springs, or left-hand springs, as the operator may desire.

Another object of my invention is to so 45 construct the adjacent and coöperating parts of the machine with reference to the reversible tool holder that wires of varying diameter may be introduced into the machine without changing the feed rolls or wire guides.

Another of my improvements consists in 50 the provision of various mechanisms, and in so combining them with the coiling tools and their supports, as to enable springs of very varied contour to be produced very

readily and without the necessity of providing special tools, dies, cams or the like, as has generally been the case heretofore. 55

A further improvement resides in a form of construction whereby the reversible tool holder is combined with pitch controlling 60 mechanism whereby the pitch of any spring may be varied automatically, and whereby springs having such varying pitch, and either right or left hand in style, may be produced without special tools, as a result 65 of certain simple and speedy adjustments.

A further improvement resides in the cutting mechanism, which is so designed with reference to the adjacent and cooperating coiling tools that the wire may be cut 70 squarely in the plane of the coil. The cutting mechanism may be very readily adjusted for different wire sizes, and for either right or left hand springs, without requiring 75 special cutters for the different spring forms.

A further object of my invention has been to provide coiling arbors of a novel type, reversible for right or left hand springs, and in so combining these arbors with the reversible tool holder and cutting devices as to enable springs of varying contour to be 80 coiled and cut on arbors of considerably smaller diameter.

Machines of this class, as heretofore made, 85 have not been either universal in scope as regards the product, or flexible as to the wire range which might be used. The feeding devices were not accurate enough, nor capable of speedy regulation and adjustment, and the machines were neither readily adjustable nor so designed that the same tools could be used for producing a wide range of springs. Special tools and cams were always necessary when a new spring 90 form was called for, and the expense and the losses of time occasioned by these limitations have always been a serious obstacle to the use of machines of this class. I have aimed to produce, as a result of my experience and experiments, a spring coiling machine of a universal type, into which a wide range of wire sizes can be introduced 95 without change of parts, and which is capable of producing a very wide range of spring forms without any special tool charge, and as a result of merely making 100 slight and speedy changes in the coöperat-

ing working members. It should be stated here that changes from one spring form to another may be made upon my machine in less than one-quarter of an hour, which 5 changes required on other types of machines from several hours to several days to accomplish.

It will be generally admitted that in 10 machines of this class such features as automatic pitch control and automatic diameter control are old in the art, and that the intermittent feeding of predetermined lengths of wire to a coiling mechanism is also old.

15 I claim, however, as novel, the construction of the specific features hereinbefore enumerated, in a machine of the character claimed, and in particular those structural combinations which render possible the results described in the preceding paragraphs.

Referring to the drawings:

Figure 1 represents a front elevation of my improved coiler.

25 Fig. 2 represents an end elevation looking from the left hand side.

Fig. 3 represents an enlarged view of the coiling tools as adjusted for coiling right hand springs.

30 Fig. 4 represents a similar view of these devices as adjusted for coiling left hand springs.

Fig. 5 represents a reduced sectional view taken on the line 5—5 of Fig. 3, and looking in the direction indicated by the arrow.

35 Fig. 6 is a view of the reversible tool holder perspective drawn.

Fig. 7 represents several views of my improved arbor, and

40 Fig. 8 represents a view in side elevation of the form of adjustable cams which I prefer to use in connection with the various devices to be hereinafter described.

Fig. 9 represents a sectional side elevation of the diameter controlling devices 45 mounted on the front housing.

Fig. 10 represents a similar sectional elevation, taken inside of the rear housing, and showing not only the method of driving the feed rolls, but also the automatic pitch controlling devices.

Fig. 11 represents an enlarged view in elevation of the pitch tool and its actuating devices, and

50 Fig. 12 represents a view of one of the pitch tools.

Fig. 13 represents a view in horizontal section, taken on the line 13—13 of Fig. 10 and looking in the direction indicated.

Fig. 14 is a view in elevation of the rear 60 housing, with the intermittent feed roll driving devices mounted thereon, and

Fig. 15 is a view in section on the line 15—15 of Fig. 14, looking in the direction indicated.

65 Fig. 16 is a view of the noiseless ratchet

mechanism used in connection with my intermittent feeding devices, the exterior covering having been removed, and

Fig. 17 represents a sectional view on the line 17—17 of Fig. 16, looking in the direction indicated and showing the exterior cover in place.

Fig. 18 represents a side view of the cam used for making barrel shaped springs, and

Fig. 19 represents a similar view of the 75 cam used in making coned or tapered springs.

Fig. 20 represents a similar view of the cam used in producing springs having variable pitch.

Referring to the drawings, and particularly to Figs. 1 and 2, I have preferably designed a machine in the form shown, consisting of a pair of upright sides or housings 1 and 2, fastened securely to a base frame 3, 85 the various spring forming tools and their adjusting controls being mounted upon or between these housings, and the driving mechanisms (which will be described hereafter) being suitably mounted on the base 90 and housings.

The horizontal line of the wire feed is indicated by the arrow at 4, the wire being fed through the preliminary guide 5 secured to the housing 1.

95 I provide two pairs of feed rolls 6—6, 7—7, to grip the wire 4, and push it forward into contact with the coiling tools. I also provide a pair of grooved wire guides 8 between the two pairs of feed rolls, together with an additional pair of similarly grooved wire guides 9, by which the wire is guided from the feed rolls 7—7 to the coiling tools.

It will be noted that the feed rolls and the 105 wire guides just described, occupy a relatively fixed position with relation to the frame of the machine. It will also be noted that rolls and guides are similarly provided with a number of identical grooves of different sizes—see Fig. 5—so that a wide range of wire sizes may be fed into the machine without any change of these parts, by simply inserting the wire in the groove provided for its particular size. Each groove 110 is capable of taking care of several sizes of wire, being made wide enough to admit the largest wire, and shallow enough to enable the smallest wire to be gripped between the feed rolls.

115 The upper feed rolls of each pair are attached to shafts 10 and 11 which are journaled in bearings in the housing 1, capable of a slight vertical movement and in bearings in the housing 2, which are capable of 120 a slight rocking movement in order to allow pressure to be applied by a spring 14, to press the upper feed rolls upon the wire.

125 The flat spring 14 is so mounted upon the front housing 1, as to bear with its ends upon 130

the vertically adjustable bearings in which these shafts 10 and 11 are carried, and pressure may be applied to the bearings, through the spring 14, by means of a threaded stud 15 and hand wheel 16, mounted intermediate between the feed rolls in the housing 1.

It should be noted, as shown in Figs. 1, 4, 5 and 6, that the wire guides 8 and 9 are fastened securely to the housing 1. The two pairs of feed rolls 6 and 7 are geared together for synchronous rotation as illustrated in Fig. 10, and are driven intermittently in a manner to be hereinafter described.

As the wire is gripped between the feed rolls in the manner just described, and is fed forward toward the coiling tools, it passes over or under the arbor 17, and against the coiling point 18, this latter deflecting the wire downward or upward as shown in Figs. 3 and 4, according to the adjustment of the coiling tools, to produce either a right or a left hand spring.

An important part of my invention consists in the reversible tool holder 19: see Figs. 1, 3, 4, 5, and 6. This tool holder consists of a cylindrical block, preferably of steel, so formed as to contain a coiling arbor such as is illustrated in Fig. 7, and a pitch tool such as is illustrated in Fig. 12. This tool holder is provided with a locating groove 20, formed longitudinally in one side to coöperate with a pin 21, permanently mounted in an opening 22, in the housing 1, this opening being so formed in the said housing with relation to the line of feed of the wire and the various coiling and cutting tools, that the tool holder 19 may be adjusted laterally in said opening so as to bring the tools which it carries upon it into alinement with any one of the plurality of wire grooves in the feed rolls and the wire guides.

I provide a clamp screw 23 threaded into the housing 1, as shown in Figs. 2 and 5, for the purpose of securing the tool holder 19 in the opening 22 in any desired lateral position with relation to the line of the wire grooves in the feed rolls and wire guides.

As the wire 4 is fed forward by the feed rolls against the coiling point 18 for the forming of a spring, it is desirable to provide means to prevent it "bowing" between the end of the guide 9 and the coiling point 18, and for this purpose I provide a small grooved member 24, which is secured to the end of the tool holder 19,—see Figs. 3 and 4,—and which is not only capable of vertical adjustment with relation to the wire line by reason of a slotted hole through which the fastening screw 25 is passed, but is also capable of being adjusted laterally with the tool-holder 19, of which it forms a part, with relation to the line of feed of the wire.

With my improved coiler I usually provide several of these guides 24, each one be-

ing adapted to coöperate with a different size of wire groove in the stationary guides 9, and feed rolls 7. As shown in Figs. 3 and 4, these adjustable guides 24 are reversible, and may be used for the coiling of either right or left hand springs. Threaded holes 26, to receive the fastening screw 25, are formed in each end of the cylindrical tool-holder 19.

The form of arbor 17 which I prefer to use in my machine, is, I believe, novel and is fully disclosed in Fig. 7. These arbors are made of steel, hardened. The shanks are preferably made of the same diametral size to enable them to enter the opening 27, formed in the tool holder 19. This circular opening extends throughout the tool holder from end to end and is located eccentrically to the axis of the holder, so that the arbor may be inserted from either side as desired, and so that the arbor may be in proper position when the tool-holder is reversed for the coiling of springs of a different hand. When the tool-holder has been inserted in place in the machine, a slight pressure of the clamping screw 23 will suffice to keep it in a properly adjusted position until the arbor 17 has been inserted and has been also properly adjusted with relation to the line of wire feed, and with relation to the cutting tools, after which the clamping screw 23 may be tightened upon the flattened face 28 of the tool-holder sufficiently to retain the arbor in place. This clamping effect is accentuated by means of the slot 29, formed in the tool-holder 19 from end to end, and across the axis of the opening 27 as shown in Fig. 6.

The arbor 17, illustrated in Fig. 7, is provided at each end with a tip 30 substantially semicircular in cross section, that on one end being adapted to wind a right hand coil, and that on the opposite end, a left hand coil. One of the edges 31 of the tip cooperates with a cutting tool in severing the wire as hereinafter described. The tip 30 is supported at an oblique angle to the line of feed of the wire and below the line of feed for a right hand coil, as shown in Fig. 3, and above the line of feed for a left hand coil, as shown in Fig. 4.

The coiling point 18 consists of a member formed preferably of steel, hardened, and grooved in one end in the vertical face against which the wire makes contact during the coiling operation. I provide several of these coiling points, each one having a groove of a different size to coöperate with the different sizes of wire grooves in the stationary guides and feed rolls.

I preferably form the housing 1, as shown in Fig. 2, at 32, to contain the slide 33. This slide is capable of being reciprocated to and fro, approximately in the center of the line of wire feed viewed horizontally, by means

of the crank arm 34, as shown in Figs. 3 and 4, this crank arm being carried in a bearing provided in the housing 1, and extending therethrough, as shown in Fig. 9, for automatic operation, as will be hereafter described.

The slide 33 is provided with a pin 35, projecting laterally across the line of wire feed, to which pin the member 36, in which the 10 coiling point 18 is carried, is adjustably secured or clamped. It will be obvious that the coiling point 18 in its support 36, may be adjusted laterally so as to coöperate with any one of the wire grooves in the fixed 15 wire guides and feed rolls, and that this support may also be adjusted radially upon the pin 35 so as to swing the coiling point to any desired position with reference to the horizontal line of wire feed.

20 In order that the lateral adjustment of the block 36 may be preserved, should it be desirable to remove it from the machine for any purpose, I further provide an adjusting set screw 37, as shown in Figs. 3 and 4, which 25 bears against the outward vertical face of the slide 33, and which may be used either to obtain a very fine adjustment of the point 18, or to preserve such adjustment, if once obtained.

30 The coiling point 18 is secured in a recessed portion of the carrying block 36, and is held in position by means of the clamp 38 and screws 39,—see Figs. 3 and 4.

It will be obvious that the coiling point 35 18 may be adjusted laterally and vertically to coöperate with any of the wire grooves, and may be used equally for right or left hand coiling. I frequently form these coiling points with wire grooves in each end, 40 so that the same coiling point may either be used for two different sizes of wire, or will have a double lifetime in actual use.

Referring to Figs. 3, 4 and 5, attention is directed to the pitch tool 40, which is carried in the opening 41 of the tool holder 19, and is formed somewhat as shown in Fig. 12. These pitch tools are of different shapes at that point where the wire spiral comes into contact with them, and different forms 45 of springs require different forms of tools, for which I have made provision in my improved machine. The function of the pitch tool 40 is to deflect the coil after it has been formed, and to give to it the necessary pitch, 50 or space between the coils. This tool slides easily in the opening 41, in the tool holder 19, and is connected at the rear end to a link 42,—see Fig. 11,—in such manner as to be speedily connected or disconnected 55 whenever it is necessary to change from right to left hand springs, the link 42 and its operative connections being so positioned as to allow the pitch tool 40 to be connected for the pitching of either right or left hand 60 springs, as shown in Figs. 3, 4, and 11.

Summarizing the various operations in the coiling of a straight, open coil compression spring so far as they have been described it will be noted that the wire 4 is fed forward against the coiling point 18 by 70 means of the feed rolls 6—6, 7—7, and is thereby deflected around the arbor 17, the amount of this deflection, and the consequent diameter of the resulting coil being determined by the relative positions of the 75 coil point 18, and the coiling arbor 17, as is well known.

After the coil has been formed, the pitch tool 40 presses against the end in such manner and to such an extent as to deflect the 80 wire continuously into a series of spirals of the required pitch.

As soon as the feed rolls have stopped (their driving devices being of an intermittent character as will be hereinafter described) cutting devices come into operation 85 to effect the severing of the wire at the arbor.

One of the principal improvements on my machine consists in the provision of two cutting devices, one of which is used when right hand springs are being coiled, the other being used when left hand springs are being coiled. These cutting devices are illustrated clearly in Figs. 1, 2, 3 and 4, and will now 95 be described.

The cutting tools 43, 44, consist preferably of a rectangular piece of steel suitably mounted by means of clamps 45 and 46, or other suitable fastenings, upon the ends of 100 the radially-swinging heads 47 and 48. These arms to which the cutting tools are secured are preferably recessed in an angular direction to receive these tools, and are so mounted, with reference to the coiling tools 105 as to allow the end of the cutting tool 43, or 44, to coöperate with the cutting edge 31 of the arbor 17, the effect of such coöperative action being to sever the wire, leaving a small portion of the coil still wrapped around 110 the arbor, and in contact with the coiling point 18.

Referring to Figs. 2, 3, 4, and 14, it will be noted that each of the cutter heads 47 and 48 is formed upon a cylindrical member or 115 shaft mounted in the housings 1 and 2 for rotation and coupled together, as shown in Fig. 14, by means of the end clamps 49 and link 50. The lever 51, Fig. 2, connecting these cutting members with the driving mechanism, is securely fastened to the lower shaft which carries the lower cutter head 47, and is operated by means herein- 120 after to be described.

It will be obvious that the movements of 125 the cutter heads 47 and 48 take place in synchronism and that in order to bring either cutter into operative relation to the coiling tools it is only necessary to adjust the desired cutting tool 43 or 44 into operative relation 130

with the arbor 17 in connection with which it is to be used, and to so adjust the cutter which is not in use that it will not interfere with said coiling operations. See Figs. 3 and 4.

The cutter arms 47 and 48 are laterally adjustable in their bearings in the housings 1 and 2, and may, by means of the set collars 52, Fig. 2, be adjusted so as to bring the cutting tools into operative relation with the arbor when the latter has been adjusted for any one of the different grooves in the stationary guides and feed rolls.

It is possible, in my improved spring coiling machine to produce straight, close wound springs, by adjusting the set screw 53 so as to bear against one of the vertical faces of the crank arm 34 (see Figs. 1, 2, 3, and 4), thus limiting the travel of the slide 32 and keeping a constant relation between the arbor 17 and the coiling point 18 during the coiling operation.

It is also possible, keeping the above adjustments, to produce a straight open coil spring by using the pitch tool 40, this tool being pressed against the end of the coil and deflecting each coil as formed to the desired extent to produce the necessary pitch.

Such forms are the simplest to produce, but it is, moreover, possible in my improved spring coiling machine to produce a very large number of spring forms of varying contour, such as coned springs, barrel springs, two-diameter springs and the like, and I will now describe the method by which these may be coiled on this machine, without the necessity of introducing special tools for each spring form, as has heretofore been the case.

As previously stated the coiling point 18 and its carrying member 36 may be reciprocated to and from the arbor 17 by means of the associated slide 33 and crank arm 34, and such movement affects the diameter of the spring being produced, by varying the distance between the arbor 17 and coiling point 18. Automatic movements of this kind are transmitted to the crank arm 34, (see Figs. 2 and 9) from the cam 54, through the cam roll 55, cam lever 56, auxiliary lever 57, link 58, and clamp arm 59 as shown. The arm 59 is firmly secured to an extended portion of the crank arm 34, and the link 58 connects the arm 59 and the auxiliary lever 57. Both of the levers 56 and 57 are preferably mounted as shown on opposite sides of the cam shaft 60, and in such a manner that any movements of the actuating cam 54 may be varied in transmission from the cam lever 56 to the auxiliary lever 57, by means of an adjustable interponent,—such, for instance, as the block 61, which may be slid along the lever 57 and fastened thereon in any desired position so as to change the relative movements of these two levers, and the

consequent movements of the crank 34, slide 33, and coiling point 18.

It will be obvious that an automatic variable movement may be transmitted from a properly formed cam 54 to a coiling point 18, so as to vary the distance of the latter from any fixed point (such as the arbor 17). The practical effect of such a variation, occurring during the coiling periods, is to change the diameter of the spring being formed.

I have found that every kind of barrel shaped spring ordinarily used may be produced by means of a cam formed as shown in Fig. 18, the various adjustments which can be introduced by means of the adjustable interponent or block 61, and by constructing the link 58 of a readily adjustable kind, being sufficient to take care of the variations usually found in springs of this description. I preferably use an extension spring such as is designated by 62 in Fig. 9, to keep the cam roll 55, in contact with the cam 54; or, when the adjusting screw 53 alone is being used to limit the travel of the crank arm 34 away from the arbor, to exert the necessary force upon the arm 34 to move it in the direction of the adjusting screw.

It has been stated that in the coiling of any kind of straight springs the position of the coiling point 18 is adjusted by means of an adjusting screw 53, in contact with a vertical face of the crank arm 34, and I utilize this form of design to effect the coiling of straight springs having one or both ends coned or reduced, by so adjusting the coiling point 18 that the spring is begun and finished on the cam 54, (producing the coned ends,) while the coiling of the straight intermediate portion is done while the crank arm 34 is banked on the set screw 53.

The automatic coiling of tapered or coned springs is effected by means of a cam 63, formed similarly to the one shown in Fig. 19, the cam 54 being removed from the machine, and the new cam 63 substituted in its place for this purpose.

By referring to Figs. 10 and 13 it will be obvious that such substitution may be effected very readily, the cam being held in place on the cam hub 64 by means of the clamping washer 65, and its fastening screws 66. The cam hub 64 is, of course, permanently secured to the cam shaft 60 in a suitable manner. As soon as the clamping member 65 is loosened and slid away from the hub a short distance, any cam which happens to be in use on the machine at the time may be removed laterally from the hub, and from the machine without any further trouble, since it is provided with an opening to pass over the shaft 60.

As stated, I use a cam of the form shown in Fig. 19 for the production of all varieties of tapered or coned springs, by substituting such a cam for the one designated as 54, and

utilizing the same cam lever and link system to operate the crank arm 34 in the manner just described. To accomplish this result the cam 63 is so adjusted as to allow 5 the coiling of a coned or tapered spring to begin at the smallest end, the cam roll 55 being then farthest from the center of the cam; and as it progressively advances toward the center the spring coils grow larger 10 in diameter. Adjustments to vary the spring diameter, or the rate of increase in diameter, are made, as before, by means of the sliding interponent 61, and the adjustable link 58.

As in the case of the barrel cam 54, the 15 taper cam 63 may be used in conjunction with the limiting adjusting screw 53 to produce odd forms of springs, the diameter control being effected for a part of the time by means of the cam, and for the remaining time 20 by means of the set screw.

One or both of the cams 67 shown in Fig. 8, which are ordinarily used for pitch-control purposes, may be used for diameter control in place of the cams 54 and 63, or may 25 be used in conjunction with these cams or in conjunction with the screw 53, for producing odd forms of springs.

For instance, one of these cams 67 may be used as a substitute for producing straight, 30 two-diameter springs, the cam being adjusted for the smallest diameter of the spring to be produced and the screw 53 being adjusted for the largest diameter. In such a case the sliding interponent 61 is so adjusted 35 as to get the best form of coil as the control mechanism changes from the cam to the adjusting screw.

When it is necessary to produce a straight, two-diameter spring in which both the ends 40 are of reduced diameter, both cams 67 are employed to produce the small diameter at each end, and the screw 53 is adjusted to limit the movement of the coiling point 18 for the production of the large diameter. 45 In producing coned, two diameter springs having one straight end, (both ends being of the same diameter) I use one of the cams 67, in conjunction with the taper cam 63, beginning the spring on cam 63 and adjusting 50 cam 67 to get the straight end of the desired length.

It will be obvious that all of these changes and adjustments may be made very rapidly and speedily, and that the equipment described will enable an operator to produce 55 the specified spring forms without requiring special tools for each separate form.

In Figs. 10, 11, 12, the automatic pitch control mechanism is clearly shown. The 60 outer vertical face 68 of the pitch tool 40 in Fig. 11 is beveled so as to engage laterally the end coil of the spring that is being produced, thus imparting to it the desired amount of pitch,—or space between the coils. 65 (The pitch tool 40 shown in Fig. 11 is in-

tended for right hand coiling, and the tool shown in Fig. 12 for left hand coiling, the main difference being in the beveled vertical face.) The pitch tool 40 is operatively connected by means of the pin 69, and link 42, 70 to the upper arm of the bell crank 70. This bell crank is suitably mounted for pivotal movement,—preferably as shown in Fig. 11,—to a bearing block 71 fastened to the inside vertical face of the housing 2. An adjusting screw 72, preferably threaded into the housing 2, limits the rearward travel of the bell crank 70, and also serves to take the end thrust of the tool 40 in the ordinary pitching operations in which variable pitch 80 is not required. In using the expression “variable pitch,” I have in mind, of course, springs which are produced with a variable spacing between the coils—such as many forms of coned or tapered springs—and also 85 springs in which one or more of the end coils are laid close at one or both ends of the spring form. It is of very considerable advantage to a spring maker to be able to produce automatically springs having their end 90 coils laid close,—or “flattened,” as is the common shop phrase. Otherwise, it is necessary by subsequent operations to square the ends of the springs by heating and pressing,—methods which are, by comparison, both 95 tedious and expensive. Similarly, it is an important point to be able to coil any kind of springs with a variable, or progressive, pitch.

Returning to the devices in Figs. 10 and 100 11, the pitch cams 67 are shown mounted in operative position on the cam hub 65, secured to the cam shaft 60, with a cam roll 73, cam lever 74, auxiliary cam lever 75 and adjustable link 76, very similar in all respects to the cam and lever system shown in Fig. 9, and described in connection with the diameter control devices. In the same way an interposed sliding block 77 is used to vary the throw of the cams 67. A spring 110 78, attached to the bell crank 70 and to any convenient fixed point, tends to draw the pitch tool 40 at all times away from the spring coil being produced.

In producing an ordinary close coil spring 115 the pitch tool 40 does not come into use. When open coil springs with equal pitch throughout from end to end are desired, the link 76 is adjusted to allow the cam roll 73 to drop clear of the cam 67, and the pitch tool 40 is then adjusted laterally by means of the adjusting screw 72 the necessary amount to produce a spring of the desired pitch, the pitch tool 40 maintaining a fixed relation to the other coiling tools.

In producing open coil springs with one 120 or more of the end coils laid close, a pair of cams 67 is selected, and adjusted relatively one to another,—that is, spread out or closed together,—according to the length of the 130

- spring, before being clamped into position on the cam hub 64. The action of the cams 67 on the pitch tool 40, as transmitted through the various connections, is such that 5 the pitch tool is retracted laterally from operative connection with the spring being produced for a period corresponding to the coiling of the one or more close coils at the ends, and is moved laterally into operation 10 during the coiling of the intermediate coils so as to cause them to be properly pitched or spaced. Pitch tools 40 are provided for coiling either right or left hand springs and these may be inserted into place by taking 15 out the pin 69, and sliding the tool 40 out of the holder 19, a reverse movement replacing the other pitch tool, as soon as the tool holder 19 has been reversed in the housing 1. The link 42 is shown in Fig. 11 as 20 connected with the pitch tool 40 for a right hand coil. When a left hand coil is to be wound the reversal of the tool holder will bring the pitch tool above the line of wire feed, and in this position the link 42 when 25 attached to the pitch tool will assume the position shown by broken lines in Fig. 11.
- I show in Fig. 20 a form of variable pitch cam which I have found very useful in my improved spring coiling machine and which 30 may be briefly described as comprising a pair of cam bodies, relatively adjustable to one another, and connected by a sliding tongue-and-grooved link, extensible to a limited extent. These cam bodies 78^a, 79, 35 may be clamped in position upon the cam hub 64, in exactly the same way as the pair of cams 67, illustrated in Fig. 13. The outer surface 80 upon which the cam roll 73 contacts is made continuous by connecting links 40 81—82, connected by pivot pins at 83 and 84 to the cam bodies, and locked together as described against radial movement. This form of cam may be adjusted in itself so as to 45 vary both throw and time, and in practice advances the pitch tool 40 against the end of the spring coils as they are produced in such a manner as to correspondingly vary the pitch of the spring coiled under these 50 conditions.
- All of the cams with the exception of the cutting cam 85, Fig. 2, are so formed (see Figs. 8, 18, 19, 20,) as to be readily removed from, or replaced upon, their mountings 55 upon the cam shaft.
- The cutting mechanism hereinbefore described is operated through the lever 51, Fig. 2, secured to the shaft carrying the lower cutter head 47, the link 86, the cam lever 87, and the cam 85, secured to the cam shaft 60, 60 (see Fig. 2.)
- Power is applied to the pulley 88 secured to the shaft 89, Figs. 2 and 14, which latter is suitably mounted in bearings carried in the housing 2 and pillow block 90. Power 65 may be transmitted from the main driving
- shaft 89 to the cam shaft 60, and the intermediate feed roll driving shaft 91, in any desired manner, but I have designed and perfected a mechanical structure to be described hereinafter which I believe to have 70 particular advantages for this special purpose.
- On the main driving shaft 89, I form a toothed gear 92, Fig. 14, and on the outer end of the cam shaft 60 I mount a larger 75 spur gear 93, which meshes with pinion 92 and transmits motion to the cam shaft 60. I transform the constant circular motion transmitted to this spur gear 93 into an intermittent motion to operate the feed rolls 80 by means of the pivoted segment gear 94, which meshes with the pinion 95, the latter being in operative connection with the noiseless ratchet illustrated in Figs. 16 and 17, and driving the feed rolls intermittently as 85 will hereafter be described.
- Referring to Figs. 14 and 15, I form the spur gear to receive a crank block 96, which may be slid in dovetailed ways across the center of the gear, and which may be 90 clamped in any desired position with reference to the center of the gear 93, by means of the gib 97 and clamping screws 98. Raised portions 99 formed on the central web of the gear 93, are preferably used to 95 provide support for the crank block 96, and gib 97. To facilitate the transverse adjustment of the block 96 I provide an adjusting screw 100, threaded into the block 96, and supported against end thrust by means of a 100 bearing 101 secured to the gear 93. Suitable collars 102 may be formed on the adjusting screw 100, to coöperate with the thrust bearing 101, and the screw is provided with a squared end 103, so that it may be readily 105 turned with some suitable tool, such as a ratchet wrench.
- I provide the block 96 with a pin 104, projecting laterally therefrom, and adapted to coöperate with and engage a sliding member 105, mounted in a radial groove 106, in the gear segment 94. The segment is pivotally mounted in the machine base on the rock shaft 107, in such relation to the spur gear 93, that the circular motion of the gear 110 is transmitted, through the crank connections 96, 104 and 105, to the segment and causes the latter to oscillate across the face of the gear 93, the travel of the segment being directly proportioned to the adjustment of the crank block pin 104 away from the axis of the gear 93. Teeth formed on the outer circumference of the segment 94 engage the teeth of the pinion 95, driving it to and fro as the segment oscillates, and 115 transmitting to it any desired amount of rotation according to the adjustment of the crank block 96.
- Referring to Figs. 2, 16, and 17, the segment 94 and pinion 95 are disclosed in op- 120
- 125
- 130

erative relation to the ratchet mechanism whereby the rotation of the pinion is properly transmitted to the shaft 91 for the intermittent operation of the feed rolls.

5 In constructing the noiseless ratchet illustrated more particularly in Figs. 16 and 17, I make the central disk or ratchet wheel 108 from steel, preferably hardened afterward, and form a series of teeth 109 upon its outer 10 circumference, these teeth being formed with an included angle of about ninety degrees, and in such angular relation to the diametral axis of the wheel as to coöperate most effectively with similar teeth 110 formed in a 15 ratchet pawl 111, pivoted exteriorly to the wheel 108. The toothed ratchet wheel 108 is fastened securely to the shaft 91 by any suitable means, such as the key 112, and imparts rotation to said shaft. I provide an 20 inclosing member for this toothed wheel, consisting of a disk 113, with an annular flange 114 upon it, and further provide a cover plate or disk 115 to contact with the flange 114 and prevent the entrance of any dirt and 25 dust which might interfere with the operation of the ratchet and pawl.

The pawl 111 is pivotally mounted on a pin 116, which is secured in the cover plate 115, the pawl being substantially the same 30 thickness as the ratchet wheel 108, so that it practically fills the space between the opposite faces of the disk members 115 and 113. This pawl 111 comprises an arm 117, upon one face of which a number of ratchet 35 teeth 110 are formed, and an extension 118 approximately at right angles to the toothed arm 117. The portion 118 is rounded on two opposite faces so as to engage smoothly with the opposite faces 119, 120, of a slot 40 or opening formed in the flange 114 opposite to the pivot pin 116, for a purpose to be hereafter described.

The pinion 95 is free upon the shaft 91 and is formed with a hub 121 adapted to 45 drive tightly into an opening formed centrally in the disk 113, to which the hub 121 is keyed by a key 122, Fig. 17, so that the pinion and disk will move as one member.

The segment 94, oscillated by its crank 50 connection to the gear 93, drives the pinion 95, rotating it in either direction, according to the direction of oscillation.

Referring to Fig. 16, and assuming that the segment 94 is moving to the right, the 55 gear 95 and disk 113 would, in this case, rotate together overhand to the left. The effect of such rotation upon the pawl 111 is to throw it into engagement with the ratchet wheel 108, as a consequence of the pressure 60 of the surface 119, of the flange 114 against the extension 118, thereby rocking the pawl 111 upon its pivot 116 and carrying the toothed arm 117 into engagement with the ratchet wheel 108, driving the shaft 91 and,

through the gearing 123 and 124, Fig. 10, 65 imparting motion to the feed rolls.

As soon as the segment 94 has completed its movement to the right and has begun the reverse motion to the left the pinion and disk 113 also reverse, and commence 70 to move clockwise to the right. The immediate effect of this movement upon the pawl 111 is to throw it out of engagement with the ratchet wheel 108, the slotted flange carrying the extension 118 about the center of the pin 116, (the latter standing practically still meanwhile) until the toothed portion 117 banks against the pin 125, mounted in the disk 113. In each case the cover plate 115 does not immediately follow 80 the disk 113 when it begins to rotate, being merely held in position on the shaft 91 by frictional engagement of a suitable kind,—such for instance as is afforded by the compression spring 126 and washer 127. 85

The specific mechanical advantages claimed for this form of ratchet gearing, apart from its use in the intermittent feeding mechanism of my coiler, are for noiselessness, strength, and certainty of operation. 90

It will be clear from the foregoing description that the feeding mechanism may be adjusted, by means of the crank block adjusting screw 100, to deliver any desired amount of wire required from a fraction of 95 a coil up to the full capacity of the machine.

The number of feed rolls required varies with different sizes of machines, since more power is required to feed wires of large diameter than for small wires. 100

I preferably form all parts of the machine which come in contact with the wire, of steel, hardened, for greater durability. In the operation of my improved coiling machine the feeding mechanism is adjusted 105 to feed a length of wire sufficient to make a single spring during its intermittent movement, and the cutting mechanism is actuated to cut the spring already coiled upon the cessation of the feeding mechanism. 110

The wire is fed in the present instance in a horizontal path, either over or under the tip of the coiling arbor, and when it strikes the vertical face of the grooved coiling point which intercepts the path of the wire, a 115 slight initial bend is given to the advancing end of the wire to direct it either upward or downward for a right or left hand coil, as the case may be. If an open coil is desired, the pitch tool is placed in the tool holder in position to spread the coils as they are being made, the distance required. 120

By carrying the coiling arbor and the pitch tool in openings in the tool holder which are eccentric to its axis, the arbor and pitch tool are held in proper position for right or left hand coils by the endwise reversal of the tool holder. 125

I am able to make the changes necessary for different diameters of springs and for a great variety of coils by a few simple adjustments requiring small exercise of skill or judgment on the part of the operator.

While I have here illustrated and described my invention in forms most preferred by me, I desire it to be understood that I do not restrict myself to the precise

10 mechanical forms and terms in which I have illustrated and described my inventions: since it is manifest that such may be very widely varied by the skilled designer without departing from the essentials of my invention, and without obtaining any material change in the result produced.

Having thus described my invention, I claim:

1. In a spring coiling machine, a framework, a wire feeding mechanism, a coiling arbor having its opposite ends adapted for coiling right and left hand springs, and a holder supporting said arbor and reversibly held in said framework, whereby either end 25 of said arbor may be brought into operative position relative to the wire feeding mechanism.

2. In a spring coiling machine, a framework, a wire feeding mechanism, a tool holder held in said framework and longitudinally adjustable therein, a coiling arbor having a tip at one end adapted to coil a right hand spring and a tip at the opposite end adapted to coil a left hand spring, and 35 an eccentric opening through said tool holder for said arbor, whereby said coiling tips are brought above or below the line of wire feed by the reversal of said tool holder.

3. In a spring coiling machine, a framework, a reversible cylindrical tool holder held in said framework, and having an opening eccentric to its axis, a wire feeding mechanism, a pitch tool held in said opening whereby said pitch tool is brought above 45 or below the line of wire feed by the reversal of said tool holder.

4. In a spring coiling machine, a framework, a wire feeding mechanism, a coiling arbor having a tip provided with a curved 50 surface tangential to the line of wire feed, and a coiling point comprising a plate having a straight side normal to the line of wire feed and extending transversely across the line of wire feed, whereby the wire is 55 deflected around over the curved surface of said tip in either an upward or a downward direction.

5. In a spring coiling machine, a framework, a wire feeding mechanism, a tool holder held reversibly in said framework, a coiling arbor held eccentrically in said tool holder and provided with a coiling tip at one end adapted to coil a right hand spring, and at its opposite end with a tip adapted

to coil a left hand spring, means for adjusting the tool holder longitudinally to bring said coiling tips in alinement with the line of wire feed, and a coiling point held normal to and extending transversely across the line of wire feed, and presenting one of its 65 edges in the path of the wire as it leaves the coiling tip.

6. In a spring coiling machine, a wire feeding mechanism, a coiling arbor provided with a cutting edge, means for maintaining 70 said arbor with its cutting edge either above or below the line of wire feed, a pair of swinging cutter heads one above and one below said arbor, means for simultaneously swinging said cutter heads, and cutting 80 blades adjustably held in said heads.

7. In a spring coiling machine, a wire feeding mechanism, a coiling arbor, a coiling point comprising a plate having an edge extending transversely across the line 85 of wire feed and normal thereto, and means for varying the distance between the coiling arbor and said plate comprising an actuating cam, a swinging lever actuated by said cam, a second lever provided with a block 90 contacting with said first lever and longitudinally adjustable on said second lever, and an operative connection between said second lever and said coiling point.

8. In a machine of the class described, the 95 combination of wire feeding devices, a coiling arbor, a pitch tool, a reversible tool holder adapted to contain and support said arbor and pitch tool, means to adjust said tool holder laterally with relation to the 100 line of wire feed, and means to adjust the coiling arbor, and the pitch tool, laterally in the tool holder, and independently thereof.

9. In a machine of the class described 105 and in combination with wire feeding devices, a cylindrical tool holder adapted to support and retain a coiling arbor and a pitch tool, means to adjust said holder and said tools laterally with relation to the line 110 of wire feed, a coiling point or wire deflector, means to adjust said coiling point laterally to aline with the wire feed, wire severing devices, and means to adjust said devices laterally with relation to the line 115 of wire feed.

10. In a machine of the class described, the combination with intermittent wire feeding devices provided with a plurality of different wire grooves, stationary wire guides 120 provided with a corresponding plurality of wire grooves, a reversible tool holder, means to adjust said holder and its contained tools relatively to any one of the said wire grooves, a coiling point, means to adjust 125 said point both laterally with relation to any one of said wire grooves, and radially to coöperate with the tool holder in its

- reversed positions, wire severing devices, means to adjust said severing devices to align with any one of said plurality of wire grooves, means to adjust said severing devices to coöperate with the tool holder in its reversed positions, wire severing devices, means to adjust said severing devices to align with any one of said plurality of wire grooves, means to adjust said severing devices to coöperate with the reversible tool holder and its contained tools in its reversed positions, and means to operate said severing devices while the wire feeding devices are stopped.
11. In a machine of the class described, wire feeding devices, a reversible tool holder adapted to support and contain coiling tools, means to adjust the holder and its contained tools to different positions for producing right or left hand springs, a coiling point, means to adjust said point to coöperate with the coiling tools in the reversible holder in their different adjusted positions, means to adjust said coiling point automatically with reference to said reversible tool holder to vary the form of spring being produced, plural wire severing devices, means to adjust
- same to coöperate with the different operative positions of the reversible tool holder, and means to operate the selected severing device.
12. In a machine of the class described, an intermittent wire feeding mechanism, comprising, in combination, a rotating member, a crank adjustable upon said rotating member, a gear segment mounted for oscillation transversely to the axis of said rotating member, and having a radial groove therein, a block adapted to slide in said groove, means to engage said block and the adjustable crank member and thereby transform rotary motion into reciprocating motion, a gear meshing with the gear segment, wire feeding rolls, and a ratchet device interposed between said gear and said feed rolls, giving the latter rotation in one direction only.
- In testimony whereof I hereunto set my hand this thirtieth day of April, 1914, in the presence of two attesting witnesses.

FRANK HENRY SLEEPER.
